AIR VENT VALVE

Lewis W. Eggleston, Davison, Mich., assignor to
 Detroit Lubricator Company, Detroit, Mich., a
 corporation of Michigan

Application June 13, 1941, Serial No. 397,855

18 Claims. (Cl. 236—63)

This invention relates generally to valves and more particularly to air vent valves for heating systems.

One object of this invention is to provide a quietly operating air vent valve having a high venting rate.

Another object is to provide an air vent valve having means for separating out any entrained liquid prior to the discharge of the air from the valve.

Another object is to provide an air vent valve having means for regulating the venting rate between predetermined limits.

Another object is to provide an air vent valve having a combined means for holding the outer housing to an inner casing and holding the vent regulating means in its adjusted position.

Other objects will be apparent from a reading of the specification and appended claims.

The invention consists in the improved construction of and combination of parts to be more fully described hereinafter and the novelty of which will be particularly pointed out and distinctly claimed.

In the accompanying drawing, to be taken as a part of this specification, there is fully and clearly illustrated a preferred embodiment of the invention, in which drawing:

Figure 1 is a top plan view of an air vent valve embodying the invention;

Figure 2 is a view in central vertical section of the vent valve and taken substantially along the line 2—2 of Fig. 1;

Fig. 3 is a view substantially along the line 3—3 of Fig. 2;

Fig. 4 is a partial view of the vent valve showing the inlet thereto, and

Fig. 5 is a partial view in section of the vent inlet showing the inlet partition.

Referring to the drawing by characters of reference, the numeral 1 designates generally an air vent valve having an inner casing 2, preferably of sheet metal, and an outer surrounding housing 3, preferably of moulded material such as "Bakelite," and having an open bottom end portion. The inner contour of the housing 3 substantially conforms with the outer contour of the casing 2 and provides a tapered passageway or chamber 3^a of thin cross-section which is, in the particular vent valve shown, about .006 of an inch wide at the top and about .015 of an inch wide at the bottom. The casing 2 in cross-section is horseshoe shaped with a wall portion 4 connecting the otherwise open end of the horseshoe portion so that the casing 2 has a continuous side

wall arcuate wall portion 4^a and a channel wall portion, the channel portion having its flanges 4^b extending tangentially from the arcuate portion and converging toward the channel base portion formed by the wall 4 which is slightly bowed or curved. The upper end of the casing 2 is closed by an end wall 5 integral with the side walls and having an aperture therethrough. The lower end of the casing 2 is closed by a plate member 6 having a perpendicularly extending flange portion 1 which is sealed to the lower end portion of the casing 2 as by solder 8. The wall portion 4 adjacent its lower end is apertured to receive a hollow tubular inlet nipple 9 which is sealed and secured thereto. The nipple 9 extends substantially perpendicularly outward from the casing 2 and extends through a slot or aperture 10 in the housing 3. The slot 10 preferably opens downwardly through the lower end of the housing 3 so that the casing 2 may be inserted into the housing 3 from the housing open bottom end portion. The outwardly extending end of the nipple 9 is externally threaded as at 11 for screw-threaded connection to a radiator of a steam heating system or other steam chest 11^a to communicatively connect the interior of the radiator to the interior of the casing 2. A plate-like member 12, which may be a fibre strip, has an aperture therethrough which receives and substantially fits the outer periphery of the nipple 9 intermediate the casing 2 and housing 3. The member 12 is positioned on the nipple 9 prior to insertion of the casing 2 into the housing 3 and acts to close the slot 10 to hide the casing 2 from view. A bent portion 13 on the member 12 is held between shoulders on the casing 2 and housing 3 to hold the member 12 in position. A resilient baffle plate member 13^a extends longitudinally of and within the nipple 9 and divides the interior of the nipple 9 into an upper or air flow passageway 13^b and a lower or water flow passageway 13^c. The plate member 13^a, in cross-section, has a substantially V-shaped bowed portion 13^d with horizontally extending side flanges 13^e which engage diametrically opposite portions of the inner wall of the nipple 9. The free dimension between the outer surfaces of the flanges 13^e is somewhat greater than the diameter of the passageway through the nipple 9 so that upon insertion of the plate member 13^a thereinto, the V-shaped portion 13^d is placed under stress to hold tightly the member 13^a within the nipple 9. The V-shaped portion 13^d also provides the desired increased flow area of the upper passageway 13^b with respect to the flow

area of the lower passageway 13^c. The member 13^a extends materially beyond the outer end of the nipple 9 so that when the valve 1 is secured in the wall 11^a of the radiator section or other space to be vented, the upper and lower passageways 13^b and 13^c will extend all the way from the interior of the valve 1 to the radiator space.

A tubular casing 14 of circular cross-section has a closed top end or wall 15 and an open lower end 16 which is positioned substantially at the level of the member 13^a. The casings 2 and 14 cooperate to form a vertical up-flow passageway 16^a adjacent the wall 4 of the casing 2. The upper end portion of the side wall of the casing 14 and the adjacent portion of the wall 15 facing wall 4, are slotted or cut substantially vertically and bent downwardly and inwardly to form substantially a tangential inlet or guideway 16^b to the interior of the casing 14 from the passageway 16^a so that fluid admitted by the inlet 16^b has a rotary movement within the casing 14. The top end wall 15 has an aperture therethrough of equal size to the aperture through the end wall 5 of the casing 2. A supporting member 17 which is preferably cylindrical in shape, has a lower shoulder 18 which seats against the upper extending surface of the end wall 5, and has a downwardly extending neck portion of substantially the same cross-section as, and which projects through, the apertures in the walls 5 and 15. The supporting member extending portion has an enlarged portion 19, which may be formed as by peening, which acts to hold the walls 5 and 15 tightly together and against the shoulder 18. The end wall 21 of the housing seats against an upwardly facing shoulder 20 on the member 17 which is spaced from and above the shoulder 18. An upwardly projecting neck portion of the member 17 extends beyond the shoulder 20 and fits within an aperture extending through the upper end wall 21 of the housing 3 and acts to position the housing 3 relative to the supporting member 17 and casings 2 and 14. The supporting member 17 has a longitudinal passageway 22 extending therethrough and opening upwardly through its upper end wall and opening downwardly through its lower end wall and into the interior of the casing 14. A diametric passageway 23 extends through the supporting member 17 substantially midway between the shoulders 18 and 20 and communicatively connects the passageway 22 with a space 24 formed intermediate the housing 3 and the end wall 5 of the casing 2. The space 24 is in open communication with the passageway 3^a. The lower portion of the passageway 22 intermediate the passageway 23 and the interior of the casing 14 is of reduced diameter relative to the upper portion of the passageway 22 and which upper portion is screw-threaded as at 25. A valve seat 26 is formed at the intersection of the reduced diameter portion with the normal diameter portion of the passageway 22.

A valve member 27 is positioned within the passageway 22 and is externally screw-threaded as at 28 for screw-threaded engagement with the screw threads 25 so that a valve seating portion 29 formed at the lower end portion of the valve member 27 may be adjustably positioned relative to the valve seat 26 for controlling flow of fluid through the passageway 22. To provide for a predetermined flow through the passageway 22 irrespective of the position of the valve member 27 relative to the valve seat 26, the valve member 27

27 has a passageway 29^a opening through the lower end wall thereof concentric with the seating portion 29 so that it is always in open communication with the interior of the casing 14.

5 The other end of the passageway 29^a opens into the normal diameter portion of the passageway 22 intermediate the threaded portion 25 and the valve seat 26 so that the passageway acts to bypass fluid past the valve controlled seat 26. The 10 passageway 29^a has a flow restricting section or orifice portion 29^b which acts to limit the amount of by-passed fluid.

The valve member extends upwardly beyond the upper surface of the wall 21 and has an enlarged 15 diameter portion 30 which is externally splined and has a normal diameter screw-threaded portion 31 positioned intermediate the portion 30 and the upper end of the member 27. A combined adjustment and holding member 32, preferably cylindrical in form, has a central aperture therethrough. The lower end of the holding member aperture is of reduced diameter and internally splined for cooperation with the splines on the portion 30 so that rotation of the holding 20 or adjustment member 32 will cause rotation of the valve member 27 with consequent longitudinal movement thereof for adjusting the rate of flow of fluid through the passageways 22 and 23. It will be noted that fluid flow is from the interior 25 of the casing 14 through the reduced diameter portion of the passageway 22 and through passageway 23 into the space 24, fluid flow upward through the threaded portion of the passageway 22 being prevented by the threaded portion 28 of the valve member 27.

Subsequent to adjustment of the valve member 27 by the holding or adjustment member 32, a nut 33 having a suitable tool slot 34 such as for example, a screwdriver slot, is threaded relative to the threaded portion 31 and seats against a shoulder 35 formed at the intersection of the reduced diameter and normal diameter aperture portions of the member 32. The seating of the nut 33 forces the lower surface of the member 32 against the upper surface of the wall 21 to securely hold the housing 3 against the shoulder 20 and in its correct cooperating position on the casing 2. The internal and external splines of the members 32 and 27 respectively, act to allow the members 27 and 32 to move axially relative to each other and yet relative rotational movement therebetween is prevented. If desired, the last thread or threads of the threaded portion 31 may be deformed to prevent the nut 33 from being easily removed from the valve member 27 subsequent to assembly so that the nut 33 will be less liable to become lost or mislaid. A radially extending pointer or finger 36 of the member 32 cooperates with suitable indicia which are shown as raised lugs moulded integral with the upper surface of the wall 21 or which could be of any other known form to indicate visually the setting of the seating portion 29 relative to the valve seat 26. A raised portion 37 extends upwardly from the top surface of the wall 21 and cooperates with the finger 36 to prevent the valve member 32 from being rotated more than 360°.

Within the casing 14 there is positioned a hollow open ended float member 38, preferably circular in cross-section, which has its lower end portion extending downwardly below the lower end of the casing 14. The lower end of the float member 38 is sealed by a flexible diaphragm 39 which is moved in response to the pressure within the float member 38. The float member 38

rated out and not carried along with the venting air so that solely vapor is allowed to escape through the passageways 22 and 23.

It may now be seen that with the vent valve described, quick venting of the air from a heating system is accomplished quietly, the heating system may be balanced so that all the radiators will be heated evenly, and in the event of a high pressure of the heating medium, a reduced venting rate may be had so that liquid will not be allowed to escape from the radiators.

What is claimed and is desired to be secured by Letters Patent of the United States is:

1. In an air vent valve, an outer casing having a continuous side wall with an arcuate portion and a channel portion, the flanges of said channel portion extending tangentially from said arcuate portion and converging toward the channel base, a cylindrical inner casing fitting within said arcuate portion and having its wall defining with said channel portion an upflow passage, said inner casing having a vertical slot at the upper end of said upflow passage, said inner casing having at one side of said slot an inturned side wall portion merging with a downturned top wall portion to provide an opening and a guideway there-to, an inlet nipple secured in and opening through an aperture in the side wall of said outer casing, the nipple passageway extending above and below the plane of a lower end wall portion of said inner casing forming said upflow passage, means providing an outflow passageway from said inner casing, and an automatic valve within said inner casing and controlling said outflow passageway.

2. In an air vent valve, a casing for connection to a space to be vented and having a top wall aperture, a supporting member closing said aperture and projecting above said casing, a housing member mounted on said supporting member and extending downward around said casing to provide a downward directed discharge passageway, means engaging and securing the top wall of said housing member to said supporting member in spaced relation to the casing top wall, said supporting member having an outlet passageway leading from the interior of said casing to the space between said top walls, and an automatic valve in said casing controlling flow through said outlet passageway, said housing member confining and directing all of the fluid discharged from said outlet passageway into said discharge passageway.

3. In an air vent valve, a casing for connection to a space to be vented and having a top wall aperture, a supporting member closing said aperture and projecting above said casing, a housing member mounted on said supporting member and extending downward around said casing to provide a downward directed discharge passageway, means engaging and securing the top wall of said housing member to said supporting member in spaced relation to the casing top wall, said supporting member having an outlet passageway leading from the interior of said casing to the space between said top walls, an inlet nipple secured in and opening through an aperture in the side wall of said casing, a partition within said casing providing an upflow passageway leading from said nipple and having an aperture communicating with said outlet passageway, a baffle plate dividing said nipple internally into upper and lower flow passages, said plate having its inner end engaging and positioning the lower end of said partition, and an

automatic valve in said casing controlling flow through said outlet passageway, said housing member confining and directing all of the fluid discharged from said outlet passageway into said discharge passageway.

4. In an air vent valve, a casing having an inlet in its lower end portion and having a top wall with an aperture therethrough, a supporting member overlying said aperture and sealed to said top wall, a housing surrounding said casing and having a top wall with an aperture therethrough and having an enclosing side wall, said supporting member having a portion extending into said housing aperture, and means holding said housing to said supporting member and acting to prevent fluid flow through said housing aperture, said supporting member having a passageway leading from the interior of said casing and opening into the space between said casing top wall and said housing, the side wall of said housing cooperating with the side wall of said casing to form a passageway of thin cross-section opening downwardly from said space for exhausting fluid admitted to said space by said supporting member passageway.

5. In an air vent valve, a casing having an inlet in its lower end portion and having a top wall with an aperture therethrough, a supporting member overlying said aperture and sealed to said top wall, a housing surrounding said casing and having a top wall with an aperture therethrough and having an enclosing side wall, said supporting member having a portion extending into said housing aperture, and means holding said housing to said supporting member and acting to prevent fluid flow through said housing aperture, said supporting member having a passageway leading from the interior of said casing and opening into the space between said casing top wall and said housing, said enclosing side wall being tapered and cooperating with the side wall of said casing to form a tapered passageway of thin cross-section opening downwardly through the bottom end of said housing for exhausting fluid admitted to said space by said supporting member passageway, said tapered passageway being of increasing cross-section toward said housing bottom end.

6. In an air vent valve, a casing having an inlet in its lower end portion and having a top wall with an aperture therethrough, a supporting member overlying said aperture and sealed to said top wall, a housing surrounding said casing and having a top wall with an aperture therethrough, said supporting member having a neck portion extending into said housing aperture, said supporting member having a passageway leading from the interior of said casing and opening into the space between said casing top wall and said housing, said housing cooperating with the side wall of said casing to form a passageway of thin cross-section for exhausting fluid admitted to said space by said supporting member passageway, said last-named passageway opening downwardly through the bottom end of said housing, valve means cooperable with said supporting member passageway for controlling fluid flow therethrough and extending through said housing aperture, and means positioned externally of said housing for holding said valve means in adjusted position and for holding said housing against said supporting member to prevent fluid flow through said housing aperture.

7. In an air vent valve, a casing having an inlet

contains a quantity of trichloroethylene so that as the temperature surrounding the float member 38 is increased, the internal pressure of the trichloroethylene will increase and flex the diaphragm 39 outwardly. A valve member 40 is secured to the upper end portion of the float member 38 and has a seating surface which is engageable with a downwardly facing valve seat 41 formed at the intersection of the reduced diameter portion of the passageway 22 with a recessed passageway portion of the passageway 22. The float member 38 is limited in its downward movement by engagement of the diaphragm 39 with the upper end surface of a screw 42 which is screw-threaded through an aperture in the end wall 6 and sealed as by solder subsequent to adjustment. The screw 42 is positioned in the usual prior art manner so that, at a temperature of about 190 degrees Fahrenheit, the outward deflection of the diaphragm 39 acting against the screw 42 as a stop will cause the float member 38 to move upward so that the valve member 40 will engage the seat 41 and stop all fluid flow into the passageway 22 from the interior of the casing 14. At lower temperatures, the diaphragm 39 seating on the screw 42 will not maintain the float member 38 in a position to stop fluid flow into the passageway 22.

An annular disk valve member 43 is positioned on the valve member 40 and seats against a shoulder of the valve member 40. The member 43 has a larger internal diameter than the external diameter of the portion of the valve member 40 which it surrounds so that fluid can pass between the members 40 and 43. The shoulder 44 is so positioned relative to the lower end surface of the supporting member 17 that when the valve member 40 is in engagement with the valve seat 41 and the valve member 43 is against the shoulder 44 the valve member 43 will not engage the lower end surface of the supporting member 17. When valve member 40 is away from its seat 41, then, and then only, upon the occurrence of a predetermined fluid flow into passageway 22, the valve 43 will be moved to engage the lower end surface of the supporting member 17 thereby to reduce the rate of fluid flow into the passageway 22 from the interior of the casing 14 to a capacity which may flow between the member 43 and the member 40.

The operation of the vent valve 1 is as follows: Air and/or other vapors along with any entrained liquid from the radiator 11^a to be vented pass from the radiator 11^a through the upper passageway 13^b into the space 16^a formed intermediate the casings 2 and 14. Because of the greater restriction to fluid flow through the annular passageway formed intermediate the float member 38 and casing 14 over that through the space 16^a, the majority of the admitted substance from the radiator will pass upward through the space 16^a and then through the tangential inlet 16^b into the interior of the casing 14 above the float member 38. This material is caused to enter the casing 14 with a swirling action so that the entrained liquid is thrown out and passes by gravity down the annular space between the casing 14 and float member 38 to the bottom of the casing 2. As the liquid level rises to the level of the lower passageway 13^c it will flow there-through back to the radiator 11^a. The air and/or the vapor will flow out through the passageways 22 and 23 and down through the space 3^a formed between the housing 3 and casing 2 to atmosphere. The narrow space 3^a acts as a muffler

to prevent the usual noise caused by escaping vapor. As the temperature of the vented material increases, the temperature of the float member 38 increases and upon the occurrence of the predetermined temperature, which for example may be 190° F., valve 40 will act to engage the valve seat 41 and prevent the escape of steam from the radiator.

It sometimes happens that a large quantity of liquid is forced from the radiator through the nipple 9 into the casing 2. When this occurs the float member 38 will be lifted thereby and the valve member 40 will engage the seat 41 to prevent the liquid from escaping through the passageway 22 in the usual manner of prior art valves.

In the majority of steam or hot water heating systems the heating medium is supplied periodically to the radiators so that there is first a venting of the air from the radiators and then as the supply of heating medium is cut-off, an inflow of air to the radiators. Furthermore, there is usually in domestic systems a plurality of radiators connected to one heat generator which operates to supply heat periodically in accordance with the demand for heat as indicated by a room thermostat located in one room of the house. Upon a call for heat the heating means starts to operate, but before the heating medium can reach and heat the radiators, the air within the system must be vented. It is desirable for economical operation to vent this air at the lowest practicable pressures from the system and, which with the vent valve shown, may be done at ounce pressures instead of pound pressures as was the common practice heretofore. It is also desirable, if the entire house is to be heated evenly, to vent the air from all the radiators and connecting conduits simultaneously and in such a manner that all the radiators will be filled with the heating medium at substantially the same time. With the variations in conduit lengths and radiator sizes, it is necessary that the venting rates of the valves positioned on each radiator be adjusted so that the restriction to flow of the venting air is inversely proportional to the amount of air to be vented. In the vent valve 1 as shown, and described, this is accomplished by means of the adjustable valve member 27. The preferred method of adjusting the venting rates of the valves is to place the vent valve venting the radiator which must exhaust the greatest amount of air at full open position and then to gradually reduce the venting rates on the other vent valves until the heating medium is supplied substantially simultaneously to all of the radiators. Subsequent to adjustment, the nut 33 is screwed downwardly to lock the valve member 27 in its adjusted position and to hold the housing 3 tightly against the shoulder 20.

It sometimes happens that for one cause or another, such as the opening of the radiator control valve after the heating medium pressure has been increased by the heating means, a greater pressure of the heating medium within the radiator occurs than is normal so that the vent valve 1 would act to vent the entrapped air at such a high rate that entrained water might be discharged from the valve. In such an event the valve member 43 is lifted by the greater pressure and engages the lower end wall of the supporting member 17 thereby reducing the rate of air flow through the passageway. This reduced rate of air flow allows the entrained water to be sepa-

and having a top wall with an aperture therethrough, a supporting member positioned in said aperture and sealed to the marginal portion thereof, a shoulder on said member spaced from said top wall, a housing seating on said shoulder and surrounding said casing and having a top wall with an aperture therethrough, said supporting member extending into said housing aperture, said supporting member having a passageway leading from the interior of said casing and opening into the space between said housing and said casing and having an aperture leading from said passageway and opening through a wall of said supporting member externally of said housing, a valve member extending through said supporting member aperture and cooperable with said passageway to control flow of fluid therethrough, adjusting means carried externally of said housing and operatively connected to said valve member and operable to engage said housing top wall, and means holding said valve member in its flow controlling position and holding said housing tightly against said shoulder and in its casing surrounding position.

8. In an air vent valve, a casing having an inlet and having a top wall with an aperture therethrough, a supporting member positioned in said aperture and sealed to the marginal portion thereof, a shoulder on said member spaced from said top wall, a housing seating on said shoulder and surrounding said casing and having a top wall with an aperture therethrough, said supporting member extending into said housing aperture, said supporting member having a passageway leading from the interior of said casing and opening into the space between said housing and said casing and having an aperture leading from said passageway and opening through a wall of said supporting member externally of said housing, a valve member extending through said supporting member aperture and cooperable with said passageway to control flow of fluid therethrough, adjusting means carried externally of said housing and operatively connected to said valve member and operable to engage said housing top wall, a passageway in constant open communication with the interior of said casing and with said space, an orifice in said last-named passageway and operable to control flow of fluid through said last-named passageway, and means holding said valve member in its flow controlling position and holding said housing tightly against said shoulder and in its surrounding position.

9. In an air vent valve, a first casing having a top wall and a bottom wall, a second casing having a top wall and an open bottom end and being positioned within said first casing, said top walls having aligned apertures therethrough, means extending through said apertures and rigidly holding said casings in a fixed relative position, said extending means having a passageway therethrough and including a valve port, a float having a portion within said second casing, a valve member carried by said float and cooperable with said port to control flow of fluid therethrough, said first casing having an inlet at its bottom end and opening into the space between said casings, said second casing having at its top end an inlet thereto from said space, and means cooperable with said second casing inlet to discharge the admitted fluid against the side wall of said second casing thereby to cause any entrained liquid to be separated from the ad-

mitted fluid so that vapors solely will pass through said passageway.

10. In an air vent valve, a first casing having a top wall and a bottom wall, a second casing having a top wall and an open bottom end and being positioned within said first casing, said top walls having aligned apertures therethrough, means extending through said apertures and rigidly holding said casings in a fixed relative position, said extending means having a passageway therethrough and including a valve port, a float positioned within said casings and having a portion within said second casing, a valve member carried by said float and cooperable with said port to control flow of fluid therethrough, said first casing having an inlet adjacent said bottom wall and opening into the space between said casings, said second casing having adjacent its top wall an inlet thereto from said space, and guide means to impart rotary flow to the fluid entering said second casing through said second casing inlet thereby to cause any entrained liquid to be separated from the admitted fluid so that vapor solely will pass through said passageway.

11. In an air vent valve, a first casing having a top wall and a bottom wall, a second casing having a top wall and an open bottom end and being positioned within said first casing, said top walls having aligned apertures therethrough, means extending through said apertures and rigidly holding said casings in fixed relative positions, said extending means having a passageway therethrough and including a valve port, a float positioned within said casings and having a portion within said second casing, a valve member carried by said float and cooperable with said port to control flow of fluid therethrough, said first casing having an inlet adjacent said bottom wall and opening into the space between said casings, a tubular member secured to said inlet and opening into said space, a dividing member held in said tubular member and extending longitudinally thereof to form upper and lower passageways, said open bottom end terminating substantially at said dividing member, said second casing having adjacent its top wall an inlet thereto from said space, and means cooperable with said second casing inlet to discharge the admitted fluid against the side wall of said second casing thereby to cause any entrained liquid to be separated from the admitted fluid so that vapors solely will pass through said extending means passageway.

12. In an air vent valve, a first casing having a horseshoe shaped portion with a side wall closing the otherwise open end of said horseshoe portion and having a top wall and a bottom wall, a hollow tubular inlet member carried by said side wall at the bottom end of said casing and in open communication with the interior of said casing, a longitudinally extending dividing member within said tubular member and forming upper and lower passageways through said tubular member, said top wall having an aperture therethrough at the center of curvature of said horseshoe portion, a second casing having a cylindrical side wall and having a top wall, said second casing top wall having a central aperture therethrough, means holding said top walls adjacent each other in fixed relation and with said apertures in alignment, said first and said second casings cooperating to form a passageway for fluid adjacent said first casing side wall and communicating with said upper passageway, said second casing having at its top end an inlet lead-

ing into the interior of said second casing from said last-named passageway, means cooperable with said last-named inlet to discharge the admitted fluid toward said cylindrical side wall, and outlet means leading from the interior of said second casing and extending through said apertures.

13. In an air vent valve, a first casing having a horseshoe shaped portion with a side wall closing the otherwise open end of said horseshoe portion and having a top wall and a bottom wall, a hollow tubular inlet member carried by said side wall adjacent said bottom wall and in open communication with the interior of said casing, a longitudinally extending dividing member within said tubular member and forming upper and lower passageways through said tubular member, said dividing member having a resilient portion acting to hold the edge portions of said dividing member tightly against the inner surface of said inlet member, said top wall having an aperture therethrough at the center of curvature of said horseshoe portion, a second casing having a cylindrical side wall and having a top wall, said second casing top wall having a central aperture therethrough, means holding said top walls adjacent each other in fixed relation and with said apertures in alignment, said first and said second casings cooperating to form a passageway for fluid adjacent said first casing side wall and communicating with said upper passageway, said second casing having adjacent said second casing top wall an inlet leading into the interior of said second casing from said last-named passageway, and outlet means leading from the interior of said second casing and extending through said apertures.

14. In an air vent valve, a first casing having a horseshoe shaped portion with a side wall closing the otherwise open end of said horseshoe portion and having a top wall and a bottom wall, a hollow tubular inlet member carried by said side wall adjacent said bottom wall and in open communication with the interior of said casing, a longitudinally extending dividing member within said tubular member and forming upper and lower passageways through said tubular member, said top wall having an aperture therethrough at the center of curvature of said horseshoe portion, a second casing having a cylindrical side wall and having a top wall, said second casing top wall having a central aperture therethrough, means holding said top walls adjacent each other in fixed relation and with said apertures in alignment, said first and said second casings cooperating to form a passageway for fluid adjacent said first casing side wall and communicating with said upper passageway, said second casing having adjacent said second casing top wall an inlet leading into the interior of said second casing from said last-named passageway, outlet means leading from the interior of said second casing and extending through said apertures, said second casing having an open bottom end positioned substantially in the plane of said dividing member, a float member positioned within said second casing, and a valve member carried by said float member and cooperable with said outlet means to control flow of fluid therethrough.

15. In an air vent valve, a first casing having a horseshoe shaped portion with a side wall closing the otherwise open end of said horseshoe portion and having a top wall and a bottom wall, 5 a hollow tubular inlet member carried by said side wall adjacent said bottom wall and in open communication with the interior of said casing, a longitudinally extending dividing member within said tubular member and forming upper and lower passageways through said tubular member, 10 said top wall having an aperture therethrough at the center of curvature of said horseshoe portion, a second casing having a cylindrical side wall and having a top wall, said second casing top wall having a central aperture therethrough, means holding said top walls adjacent each other in fixed relation and with said apertures in alignment, said first and said second casings cooperating to form a passageway for fluid adjacent said first casing side wall and communicating with said upper passageway, 15 said second casing having adjacent said second casing top wall an inlet leading into the interior of said second casing from said last-named passageway, outlet means leading from the interior of said second casing and extending through said apertures, said second casing having an open bottom end positioned substantially in the plane of said dividing member, a temperature responsive member positioned within said second casing, a valve member carried by said second casing having adjacent said second casing top wall an inlet leading into the interior of said second casing from said last-named passageway, and means carried by said first casing bottom wall and acting to determine the temperature at which said valve member engages said outlet means.

16. In an air vent valve, a casing having an outlet port, an automatic valve in said casing and operable to close said outlet port, an inlet nipple secured to and opening into said casing, and a resilient baffle plate dividing said nipple internally into parallel flow passages, said plate being compressed transversely by the nipple walls to hold said plate tightly in position.

17. In an air vent valve, a casing having an outlet port, an automatic valve in said casing and operable to close said outlet port, an inlet nipple secured to and opening into said casing, and a baffle plate dividing said nipple internally into an air inflow passage and a water outflow passage, said plate being of trough-like transverse cross-section so that said air passage is of greater flow area than said water passage.

18. In an air vent valve, a casing having an outlet port, an automatic valve in said casing and operable to close said outlet port, an inlet nipple secured to and opening through the side wall of said casing, and a baffle plate extending materially outward from the inlet end of and dividing said nipple internally into an upper air inflow passage and a lower water outflow passage, said plate having a longitudinally extending central V-section with horizontal side flanges engaging diametrically opposite portions of the nipple wall so that said upper passage is of greater flow area than said lower passage.
